PRESSURESTAT

James E. Browning, San Antonio, Tex., assignor of one-half to Claude V. Birkhead and Werner N. Beckmann, both of San Antonio, Tex., copartners doing business as Birkhead, Beckmann, Stanard & Vance

Application April 12, 1938, Serial No. 201,636

4 Claims. (Cl. 137—156)

The invention relates to improvements in devices for use in connection with pressure containing systems of various sorts, to perform work of one kind or another when operated by the system-contained pressure. Exemplary applications of the invention are in connection with steam boilers to control the water boiling means, and in connection with liquefied petroleum plants which require heat to volatilize the liquefied petroleum in cold winter months or when an excess amount of gas is to be used. Obviously rise in pressure of the fluid or vapor in the boiler or in the liquefied petroleum tank may be utilized to diminish the amount of heat applied, and vice versa, and the present invention is well adapted to function in this manner, particularly when used to actuate the burner control and ignition means disclosed in my United States patent application Serial No. 188,159, filed

February 1, 1938.

The object of the invention is to provide a novel device responsive to pressures only at a predetermined high pressure and a predetermined low pressure, also a device that will operate with a quick action. The fuel supply and ignition means or other means actuated by the pressurestat will not, therefore, continually fluctuate, but will be operated only at a predetermined high pressure and a predetermined low pressure.

With the foregoing in view, the invention resides in the novel subject matter hereinafter described and claimed, description being accomplished by reference to the accompanying drawings.

Fig. 1 is a vertical sectional view through the pressurestat, showing the parts thereof in neutral position.

Fig. 2 is a fragmentary view similar to a portion of Fig. 1 but illustrating the relation of parts which occurs when the predetermined high pressure has been reached.

Fig. 3 is a view similar to Fig. 2 but showing the relation of parts which occurs when the predetermined low pressure has been reached.

A preferred construction has been illustrated and will be rather specifically described, with the understanding however, that within the scope of the invention as claimed, variations may be made.

A casing 5 is provided, said casing being divided by a partition 6 into two chambers 7 and 8, said partition being provided with openings 9 surrounded by one valve seat 10 which faces the chamber 7, and being provided with another

opening 11 surrounded by a valve seat 12 which faces the chamber 8. The casing 5 is provided with a threaded nipple or the like 13 communicating with the chamber 7 for connection with any pressure-containing system with which the invention is to be used. The nipple 13 is shown threaded into a boss 14 on a tank 15 which may be considered as a water boiler or as a tank containing liquefied petroleum. For explanatory purposes, it will also be assumed that heating means is provided for the tank contents and that the pressure-actuated member 16 which is subjected to the pressure in the chamber 8, controls said heating means in one way or another to supply heat when tank-contained pressure diminishes to a predetermined extent and to discontinue or diminish the heat when the tank-contained pressure increases to a predetermined extent.

One valve 17 is cooperable with the seat 10 and is provided with a spring 18 for closing and holding it seated, except when such pressure differences exist in the two chambers 7 and 8, as to open said valve. Another valve 19 is cooperable with the seat 12 and opens in the opposite direction from the valve 17, that is toward the chamber 8 instead of toward the chamber 7. A spring 20 is provided for closing this valve 19 and holding it closed until sufficient pressure exists in the chamber 7 to effect valve opening.

For illustrative purposes, the valves 17 and 19 are shown provided with appropriate stems 21 and 22 respectively, slidably engaged with suitable guides 23 and 24, the former being carried by the partition 6 and the latter by a head 25 secured in an opening 26 of the casing 5, by a screw plug 27. Stem 21 is provided with a collar 28 against which one end of the spring 18 abuts, the other end of said spring being disposed against the partition 6. The guide 24 is provided with a collar 29 against which one end of the spring 20 abuts, the other end of this spring being disposed against the valve 19. Both collars 28 and 29 are preferably adjustable to vary the strength of the springs 18 and 20, and for illustrative purposes, I have shown nuts 30 and lock nuts 31 for adjusting and locking said collars.

The pressure-actuated work-performing member 16 is preferably in the form of a Sylphon bellows having an end flange 32 clamped under a plate 33 forming part of the casing 5, said plate having openings 34 communicating with the interior of said bellows. The plate 33 is also provided in the present disclosure with an adjustable plug 35 through which a rod 36 passes slidably,

said rod being connected in any suitable way with the inner end of the bellows. This rod is surrounded by a spring 37, the upper end of which abuts a collar 38 contacting with the lower end 5 of the plug 35, the lower end of said spring being either disposed against the lower end of the bellows or against some suitable abutment (not shown) carried by the rod 36. Obviously, by adjusting the plug 35, the strength of the spring 10 37 may be varied, and this strength is always greater than the strength of the spring 18, for the inner end of the bellows 16 is adapted to abut the stem 21 of the valve 17 under predetermined low pressure, the spring 37 then overcoming the 15 spring 18 and holding the valve 17 open.

Obviously, movement of the bellows 16 caused by a predetermined low pressure in the chamber 8, will move the rod 36 downwardly whereas movement of said bellows in the other direction, 20 under a predetermined high pressure in said chamber 8, will move said rod in the opposite direction, and these movements of the rod may be utilized to control the tank-heating means, in any suitable way.

25 As the pressure in the chamber 7 increases to a predetermined high pressure, the valve 19 is forced open as shown in Fig. 2. This allows the pressure from chamber 7 to pass into chamber 8 and causes the bellows 16 to collapse as 30 shown in Fig. 2, thus causing the rod 36 to travel upwardly to diminish or discontinue the application of heat to the tank, thereby preventing an increase of pressure above the predetermined high pressure desired in said tank. As the liquid or vapor in the tank cools and the pressure in chamber 7 decreases, valve 17 opens sufficiently to equalize the pressure in the chambers 35 7 and 8. When this pressure becomes equalized, valve 17 closes and with the aid of the pressure 40 in chamber 8, exerts sufficient pressure (as determined by springs 37 and 18) to hold bellows 16 and rod 36 in the neutral position shown in Fig. 1, thus avoiding a premature actuation of the heat-controlling means. If, and as long as, the 45 pressure in chamber 8 is less than that in chamber 7, valve 17 will remain closed, holding rod 36 in neutral position. When a predetermined low pressure is reached in chamber 7, valve 17 opens, thus causing the existence of a similar 50 pressure in chamber 8. This causes bellows 16 to expand as shown in Fig. 3, moving valve 17 from its seat (by the superior strength of spring 37) causing rod 36 to move in a direction to continue the application of heat to the tank. As 55 pressure rises in the tank, valve 17 will close, whereupon its stem 21 forces against the bellows 16, again holding said bellows in the neutral position of Fig. 1 until the predetermined high pressure is again reached, at which time all actions 60 are repeated. Attention is invited to the fact that the bellows 16 is entirely free from connection with both valves 17 and 19. This insures that the bellows cannot cause valve fluctuation. In fact, the entire structure is such that 65 it will not operate until the predetermined high pressure or the predetermined low pressure is reached, at which time the device will perform its duty with substantially an instantaneous action.

70 As excellent results may be obtained from the details shown and described, they are preferably followed. However, as above stated, variations may be made within the scope of the invention as claimed.

I claim:

1. A pressurestat comprising pressure-actuated work-performing means movable in one direction when subjected to relatively high pressure and movable in the other direction when subjected to relatively low pressure, two valves, and a casing structure cooperable with said work-performing means and said valves in forming one chamber to receive the actuating pressure for said work-performing means, said casing structure having provision for so connecting it with a pressure-containing system that both of said valves control communication between the system and the one chamber aforesaid, said casing having one opening cooperating with one 15 of said valves to place this one chamber in communication with the system when said one valve is subjected to a predetermined low pressure in the system, said casing also having another opening cooperating with the other valve to place the same chamber in communication with the system when said other valve is subjected to a predetermined high pressure in the system, whereby said work-performing means will be operated upon the existence of predetermined high and low 20 pressures, said chamber being closed against entrance and exit of pressure except by way of said openings, said work-performing means being free from connection with said valves.

2. A structure as specified in claim 1; said 30 work-performing means being so related with said one valve that the movement of said work-performing means in said other direction will open said one valve and hold it open until sufficient pressure is restored in said chamber to 35 free said work-performing means from said valve.

3. A pressurestat comprising a casing divided by a partition into two chambers, said partition having one valve seat facing one of said chambers, a second valve seat facing the other of said chambers, and openings surrounded by said valve seats, means for placing said one of said chambers in communication with a pressure-containing system, said other of said chambers 40 being closed against entrance and exit of pressure except by way of said openings, a pressure-actuated work-performing member subjected to the pressure in said other chamber, the movement of said work-performing member under reduced pressure being toward said one seat and vice versa, one spring-closed valve cooperable with said one seat to open when subjected to a predetermined low pressure in said one chamber, said valve being so related with said work-performing member that said movement of said work-performing member under reduced pressure will open said one valve and hold it open until predetermined pressure has been restored in said other chamber, a second spring-closed 45 valve cooperable with said second seat to open when subjected to a predetermined high pressure in said one chamber, and a spring for moving said work-performing member in the direction in which said one valve opens, this spring 50 being of greater strength than the spring which closes said one valve, said work-performing member being free from connection with said valves.

4. A pressurestat comprising a casing having 70 means at its inner end for placing it in communication with a pressure-containing system, said casing having a partition between its inner and outer ends dividing it into two chambers, said partition having one valve seat facing the inner- 75

most of said chambers, a second valve seat facing the outermost of said chambers and openings surrounded by said valve seats, said outer chamber being closed against entrance and exit of pressure except by way of said openings, a pressure-actuated work-performing member passing through the outer end wall of said casing, a Sylphon bellows around the inner end of said work-performing member and fluid-tightly associated with the latter and said outer end wall to prevent escape of pressure from said outermost chamber, a spring associated with said work-performing member and urging the same and said Sylphon bellows inwardly, the movement of said work-performing member at reduced pressure being effected by said spring, one spring-closed valve cooperable with said one seat to open toward said inner chamber when subjected to a predetermined low pressure in said inner chamber, said valve being so related with said Sylphon bellows that said inward movement of said work-performing member and bellows under reduced pressure will open said one valve and hold it open until predetermined pressure has been restored in said inner chamber, and a second spring-closed valve cooperable with said second seat to open toward said outer chamber when subjected to a predetermined high pressure in said inner chamber, the spring of the first named valve being of less strength than the spring associated with said work-performing member, said valves being free from connection with said work-performing member. 5 10 15
